UNITED STATES PATENT OFFICE.

JAMES B. SWORD, OF PHILADELPHIA, PENNSYLVANIA, ASSIGNOR TO SWORD & KIMBER COMPANY, OF PHILADELPHIA, PENNSYLVANIA, A CORPORATION OF DELAWARE.

METHOD OF AND APPARATUS FOR BURNING FUEL.

Application filed March 1, 1924. Serial No. 696,119.

To all whom it may concern:

Be it known that I, JAMES B. SWORD, a citizen of the United States, residing in the city and county of Philadelphia, State of Pennsylvania, have invented certain new and useful Improvements in Methods of and Apparatus for Burning Fuel, of which the following is a specification.

My invention relates to a method of and apparatus for burning fuel, such as coal, finely divided solid fuel, and more particularly fluid fuel, such as gas, and particularly oil, or oil in finely divided state, and particularly when in the vapor or gaseous phase, for combustion or heating purposes in general, and more particularly for generating heat in a furnace or fire box of any type of heat transfer structure, such as the boilers, heaters or furnaces supplying heated medium for heating residences, apartment houses, office buildings and the like.

In accordance with my invention, preliminary or low rate combustion is effected by burning the fuel in a fire pot, mixing chamber or preliminary combustion chamber while in mixture with gases comprising products of combustion and oxygen, the latter present in proportion less than in air or insufficient to maintain and effect high rate of and substantially perfect combustion, the aforesaid gases being circulated, as by a blower or equivalent, from within the furnace, fire box, flue or chimney to the interior of the fire pot, mixing chamber or preliminary combustion chamber, the aforesaid preliminary combustion being followed by the principal and substantially complete combustion at higher rate, both stages of combustion being accompanied by admission of air into the system at such rate or in such quantity as finally to effect complete or substantially complete combustion, without, particularly in the case when the fuel is oil, deposition of carbon or soot, except in inconsequently quantities.

Further in accordance with my invention, kerosene, gas oil, fuel oil, or any other suitable oil or fluid fuel is delivered at suitable rate into a chamber, as a fire pot, mixing chamber or preliminary combustion cham-

ber in which it is converted into vapor or gaseous phase, and the vaporous or gaseous fuel is therein mixed with hot gases, as oxygen in mixture with the nitrogen of air and gaseous products of combustion circulated from a point or region within the fire box or furnace external to the fire pot or preliminary combustion chamber to the interior thereof, causing the aforesaid preliminary or low rate of combustion followed in another region, as at, near or above the upper end of the fire pot, mixing chamber or preliminary combustion chamber by substantially complete combustion at higher rate.

Further in accordance with my invention, the circulating gases are preferably delivered into the fire pot, mixing chamber or burner structure, tangentially or otherwise suitably to effect a whirling or vortical movement of the mixture of circulating gases and fuel which progresses longitudinally, preferably upwardly, through the burner structure, mixing chamber or preliminary combustion chamber, the preliminary or low rate combustion of the fuel taking place during its whirling or vortical movement.

Further in accordance with my invention, the fuel is burned under conditions avoiding roar or noise.

My invention resides in the method and apparatus of the character hereinafter described and claimed.

This application is in part a continuation of my prior application Serial No. 627,057, filed March 23, 1923.

For an understanding of my method, and for an illustration of some of the various forms my apparatus may take, reference is to be had to the accompanying drawings, in which:

Fig. 1 is a perspective view of my system, partly in section, and comprising in part a diagram of a control circuit.

Fig. 2 is a vertical sectional view, partly in elevation, taken on the line 2—2 of Fig. 3, showing the mixing chamber or preliminary combustion chamber and the associated fuel-delivering structure.

Fig. 3 is a horizontal sectional view, partly in plan, taken on the line 3—3 of Fig. 2.

Fig. 4 is a transverse sectional view of oil straining structure.

5 Fig. 5 is a sectional view, partly in elevation, on the line 5—5 of Fig. 4.

Referring to Figs. 1 to 3 inclusive, H represents a wall of a fire box or heater in general, and more particularly of a fire box or heater having structure, not shown, for transferring the heat to suitable heating medium, as air, water, vapor or steam, utilized, for example, for heating a dwelling or other building. The fire box or chamber 10 F within the wall H is connected as usual to a flue or chimney, not shown.

Disposed within the fire box or furnace F is the fire pot, mixing chamber, preliminary combustion chamber or burner structure A, of any suitable form or construction, but preferably, as indicated, of circular form. The structure A may be cast or molded in a unit or in sections of any suitable material, as cast iron or other metal, or of non-metallic material, such as refractory earth materials, as fire clay, or the like.

In the example illustrated the chamber A comprises the bottom section a, which may be provided with the lugs or feet b, by which 30 the structure may stand or rest upon any suitable support, as the bottom c of the fire box or furnace chamber F. Superimposed upon the section a is the section d, upon which is superimposed the upper or top section e having the inwardly and downwardly curved ledge or flange f, forming the outlet opening g and the interior annular channel h.

40 Communicating with the interior of the structure A, as by threading into the section d, is the metallic pipe i, at whose lower side adjacent its outlet is secured the lug or member j integral with or carrying the target or impact member or disk k of any suitable shape, as circular, and preferably inclined inwardly and upwardly at any suitable angle, for example, 45 degrees. The target k is of any suitable material which will withstand the temperatures involved, and may 45 be of nichrome or any suitable refractory metal, or of carborundum, or equivalent.

Extending through the wall of the pipe i is a pipe m, controlled by valve n, having the outlet or nozzle o delivering fuel gas or illuminating gas, or equivalent, to effect a pilot flame which is directed against and heats the target k or, in general, serves to ignite the fuel, as in starting the system. Surrounding the pipes m and i is the tube p, of asbestos or other suitable material of poor heat conductivity, the tube p fitting in the opening q in the furnace wall H and at its inner end closely approaching, or, as indicated, abutting against the structure A, 60 and provided at its lower side with the

notch or opening r through which fresh or atmospheric air enters from the exterior of the furnace wall H through the tube p and through the notch or passage r into the fire box or furnace F, exterior to the structure A, and preferably in a position such that the incoming air will impinge upon the fire pot A or otherwise be preliminarily heated.

Upon the outer end of the pipe i is disposed the fuel-delivery structure D comprising the cap s threaded on the end of the pipe i and the cylinder t threaded into the reduced end of the cap s. At its left end the cylinder t is provided with the small nozzle orifice u communicating with the small bore v, which in turn communicates with the larger bore w, in which is disposed the plunger or piston x having the portion y of reduced diameter adapted to abut against the left end of the larger bore w and thereby close the inlet to the small bore v. Movable with the piston x and extending to the left of the reduced portion y is the pin or needle z, of a size adapted to pass through and preferably closely fit the orifice u when the piston structure moves toward the left from its position indicated in Fig. 2. Communicating with the bore w adjacent its left end is the pipe a¹, which delivers oil or other fluid fuel under suitable pressure. Upon the end of the cylinder t is threaded the member b¹, whose interior communicates with the bore w and with whose interior communicates the pipe c¹, which returns any oil escaping past the piston x to the fuel supply tank. Threaded into the end of the fitting b¹ is the plug or gland d¹, through which extends the longitudinally movable piston rod e¹, to which the piston x, and members y and z, are secured. Secured upon the rod e¹ is the collar f¹, between which and the plug d¹ is disposed the helical spring g¹ tending to move the piston x toward the left, as viewed in Fig. 2.

An electric motor M, receiving current from the supply circuit conductors h¹ and i¹, and controlled by the thermostat T, responsive to the temperature in any suitable part of the dwelling or building, and thereby indirectly responsive to the combustion effected within the fire box or furnace F, drives the fuel or oil pump P, whose suction is connected by the pipe j¹ with the fuel tank or reservoir R containing the oil or other liquid fuel supplied from time to time through the filling pipe t¹. The discharge of the pump P connects by pipe k¹ with the chamber m¹ of the oil strainer structure S comprising the member n¹, to which is secured by screws o¹, Figs. 4 and 5, the chambered member p¹, with which connects the aforesaid oil delivery pipe a¹. Between the gasket q¹ and the member p¹ is

clamped and held the strainer member r^1 , of metal gauze or equivalent. Connected with the opposite side of the chamber m^1 from the pipe k^1 is the oil return pipe s^1 , which 5 returns oil to the tank R.

By suitably adjusting valve s^2 in pipe s^1 , the desired degree of oil pressure within the strainer S and in the oil-delivery pipe a^1 may be procured. Connecting with the 10 return pipe s^1 through a Y fitting u^1 is the oil drain pipe v^1 , with which may connect the aforesaid pipe a^1 , and which connects with the hollowed or concave bottom a of the structure A, whereby any oil collecting there- 15 in will be returned to the tank R, the stream of oil through the pipe s^1 effecting a suction at the fitting u^1 drawing the oil through the pipe v^1 and delivering it into the tank R.

Driven by the motor M, through shaft w^1 , 20 is the rotary element of the gas-forcing or pumping structure B, which preferably takes the form of a blower or fan whose rotary element may be of the turbine, fan or other suitable or equivalent type, which 25 has the effect not only of moving gases, but also of churning them and causing their thorough intermixture and thereby eliminating stratification.

The suction of the blower B is connected 30 by the tube or duct y^1 with the interior of the heater H, or with the flue or chimney, the inlet being disposed preferably near the bottom of the fire box or furnace F or below the top of the structure A; furthermore, as 35 indicated in Fig. 1, it is preferable that the intake of the duct y^1 be inclined to facilitate withdrawal of gases from the region below to the top of structure A. The discharge of the blower B is connected by the duct 40 z^1 with the tangentially directed inlet structure a^2 , increase in velocity being effected, if desired, by the constriction or nozzle z^2 . Gases are accordingly withdrawn from the furnace F through the duct y^1 and returned 45 through the duct z^1 into the fire pot, mixing chamber, burner or preliminary combustion chamber A and delivered therein tangentially, whereby there is effected within the structure A a whirling or vortical movement of the returned gases in mixture with fuel, the target k being placed edgewise with respect to the whirling gases.

The operation is as follows:

Illuminating or fuel gas is continuously 55 supplied through the pipe m , at suitably low rate controlled by the valve n , continuously maintaining at the outlet or nozzle o , a flame which is preferably directed toward or impinges upon the impact member k , keeping 60 it at suitably elevated temperature and serving also to ignite the fuel, each time delivery of fuel is resumed.

The motor M, which is started whenever the contacts of the thermostat T close 65 the circuit, and which stops whenever the

contacts separate, in response to changes in temperature adjacent the thermostat, drives the blower B and the pump P, which latter effects a continuous forced circulation of oil from the storage tank R through the chamber m^1 of the strainer structure S parallel to one face of the strainer member r^1 and returning to the tank R through the pipe s^1 . There is accordingly a continuous stream of oil passing through the chamber m^1 , and 70 its effect is continuously to clean the strainer member r^1 , removing therefrom such particles of solids and semi-solids which may collect thereon. The pump maintains a substantial pressure within the chamber m^1 , 75 and in consequence a small portion of the circulating oil will pass through the strainer member r^1 and thence through the pipe s^1 to the fuel-delivery structure D.

Upon the resumption of oil pressure in the pipe a^1 , when the motor M starts, oil is delivered into the left end of the large bore w , into the space surrounding the member y of smaller diameter, thereby exerting a pressure on the left end of the piston x , causing it to move toward the right, in opposition to spring g , and thereby withdraw the pin or needle z from the nozzle orifice u , thereby permitting oil under pressure to be forced through the nozzle orifice u . When the motor M stops, the pressure of the oil in the pipe a^1 falls, and the spring g moves the plunger x toward the left, causing the needle or pin z to pass through the nozzle orifice u and close it. The repeated movements of the needle z through the orifice u keeps it 90 clean, removing therefrom all deposits which might otherwise accumulate in and clog the nozzle orifice.

The oil issues from the nozzle u in the form of a fine substantially solid stream indicated at b^2 , Figs. 2 and 3, which impacts upon the impact member k , where, due to the impact and the elevated temperature of the target due to its location in the combustion zone and the preliminary heating by the pilot flame, the oil is atomized or very finely divided and converted into the gaseous or vapor phase. The pressure of the oil as delivered to the nozzle u is sufficiently high, as of the order of from 20 to 50 pounds per square inch, to ensure that the oil stream b^2 shall have sufficiently high velocity when impacting upon the member k to effect and ensure atomization or vaporization or equivalent sufficiently fine subdivision of the oil. The fuel is immediately ignited by the pilot flame, and the combustion thereafter continues so long as oil is delivered through the nozzle u . The oil particles and/or the gas or vapor into which the oil is converted, are deflected upwardly by the upwardly inclined target k , into or toward the annular channel h , coming into mixture with the whirling or rotating gases, 115 120 125 130

whose movement is effected by the gases circulated through the ducts y^1 and z^1 . Inasmuch as the oil vapors or gases are heavier than the hot gases with which they are mixed, they fall or settle, and in so doing become more and more intimately mixed with the whirling gases.

There accordingly occurs within the fire pot, burner, mixing chamber or preliminary combustion chamber A combustion of the fuel, the fuel as it burns being whirled or rotated with the hot gases, and the combustion of the fuel itself produces hot gases which enter into the mixture.

15 The combustion within the structure A is preliminary or of low rate, and the combustible material is not completely burned while circulating within the structure A, or at any rate, not completely burned at or adjacent the lower portions of the chamber A.

16 The gases and burning fuel while rotating or whirling in the chamber A at the same time rise upwardly, with increasing 25 rate of combustion, and at, near or above the opening g the principal combustion takes place at materially higher rate, and this secondary or principal combustion, which is accompanied by blue, or preferably intense- 30 ly white, flame, is complete or substantially so, for little or no carbon or soot is deposited within the apparatus or within the fire chamber F or upon the surface of the heat-absorbing structure or within the flue or chimney. The flame itself will produce a slight suction which will cause air drawn in through the tube or duct p to enter into the fire box or furnace F through the aperture r outside of the chamber A, and the oxygen 35 of this fresh air comes into mixture with the burning fuel and hot gases at and above the outlet opening g , where the higher rate of combustion obtains.

40 The blower B draws hot gases from the fire box F through the duct y^1 and returns them, still hot, at a temperature of the order of 600 to 800 degrees F., through the duct z^1 tangentially into the chamber A, causing the effects described. These gases so circulated 45 by the blower B comprise products of combustion, as, for example, about 8 per cent of carbon dioxide, about 1 per cent of carbon monoxide, and about 3 to 10 per cent of oxygen. The oxygen content of the circulating 50 gases is less than the oxygen content of fresh air; and the amount of oxygen delivered into the pot or preliminary combustion chamber A is insufficient to burn all the fuel delivered into the chamber A, the dilution 55 of the oxygen being such as to sustain only low rate of and imperfect combustion. In consequence, within the preliminary combustion chamber A the amount of oxygen present is insufficient to effect complete or 60 substantially complete combustion or high

rate of combustion, but the temperatures effected within the chamber A are sufficient to vaporize or gasify the oil impinging upon the target k , and within the chamber A occurs the retarded or low rate of combustion 70 which may be accompanied to some extent by destructive distillation or cracking of the oil or a part thereof.

However, when reaching or passing the opening g , the rate of combustion increases 75 because the hot gases and as yet unburned fuel or incompletely burned fuel come into contact with more oxygen as afforded by the air entering through the passage r , and the combustion rate is increased and the combustion rendered complete or substantially so, for the gases passing out through the flue or chimney contain oxygen of the order of 2 or 3 per cent, carbon dioxide of the order of 12 or 14 per cent, and carbon monoxide to the extent of a small fraction of 1 per cent. It will be understood that all the aforesaid figures are given merely by way of example, and are descriptive rather than limitive of my invention.

80 The air passage r is preferably located at a point or region remote from the intake end of the gas circulating duct y^1 , so that oxygen shall not be delivered into the chamber A at too high a rate, and further to prevent stratification of the gases circulated through the duct y^1 . The blower B, particularly when of the type described, serves by mechanical action to circulate the gases, and has the further important beneficial effect of thoroughly and intimately churning and mixing the gases and returns the gases into the chamber A without stratification, but in thorough intermixture.

85 In operation, my combustion system is quiet, without roar or noise, since high pressure atomization of the oil is not resorted to, nor is there blasting by air, and the movement of the gases takes place at velocities 90 sufficiently low to be noiseless, combustion-supporting air taken into the system being supplied by the draft caused by either or both the combustion at the opening g and the gas circulation effected by the blower B.

95 In accordance with that phase of my invention which relates to the use of liquid fuel, as oil, the oil is delivered in a solid stream from a nozzle remote from the impact plate or point of atomization, vaporization and initiation of combustion, and there is no atomization or dispersion of the oil, nor combustion thereof, until it reaches the target or a point remote from the oil-delivering nozzle, with the result that the collection of carbon or the like at or upon the nozzle is avoided, but which would otherwise occur, as in prior 100 systems, where the combustion is initiated at the point of delivery of the oil from the nozzle. Furthermore the stream is of oil 105

only, without admixture of air, and subdivision and ignition take place only at a substantial distance from the oil discharge.

By utilizing an impact plate or target of the character described and positioned edge-wise to the whirling stream of gases, there is no sufficient region of low velocity or quietude on the lee side or edge of the target to permit production and accumulation of carbon in substantial quantity.

According to one of the aspects of my invention, there is a circulating stream of gas, containing products of combustion and a reduced amount of oxygen, the stream having a simple motion of translation from the inlet of the duct y^1 to the discharge end of the duct z^1 , except for the churning action within the blower B, and having after discharge from the duct z^1 a vertical or whirling movement, during which the fuel is introduced as such, and not in mixture with air or other combustion-supporting agent, effecting a preliminary combustion which is imperfect, because of small ratio of oxygen to fuel, and whose rate is low. It is a further characteristic feature of my invention that the fresh air admitted to the system does not reach the region of low rate of combustion, but comes into the system at a point or region beyond the introduction of the fuel and more particularly beyond the region of imperfect and low rate of combustion.

It is a further feature of my invention that the flame at or adjacent the upper end of the structure A is spread and diffused by creation, as by the described circulation of the gases of down draft in the furnace or fire box outside of the fire pot or preliminary combustion chamber A.

While I have described my invention more particularly in its relation to the employment of fluid fuel, as oil or the like, it will be understood that my invention in its broader aspects is applicable also to the burning of coal or solid fuel, as in the fire box of a heater or furnace, in which case the stream of gas comprising products of combustion and reduced amount of oxygen may be circulated from the fire chamber or furnace back to and through the bed of coals within which bed low rate of combustion will be effected, followed by higher rate of combustion as effected by incoming fresh air introduced or becoming effective at a point or region above or beyond that at which the preliminary or low rate of combustion takes place; and in this relation the bed of coals is in effect the mixing chamber in which preliminary combustion takes place.

What I claim is:

1. The method of burning liquid fuel, which comprises atomizing the fuel, effecting mixture thereof with a stream of whirling hot gaseous products of combustion containing oxygen sufficient only partially to

burn the fuel, and thereafter effecting substantially complete combustion in a different region in contact with oxygen of air freshly added at a point beyond the region of mixture.

2. The method of burning liquid fuel, which comprises introducing atomized fuel as such into a whirling stream of hot gaseous products of combustion containing oxygen and initiating combustion of the fuel while in said whirling stream.

3. The method of burning liquid fuel, which comprises atomizing the fuel, mixing the same with a stream of hot gases having oxygen content in lesser proportion than in air, causing a whirling and longitudinal movement of the mixture to transport said fuel to a region remote from the region of first contact between said fuel and said stream, and there effecting combustion at higher rate by admixture of air.

4. The combination with a furnace, of a mixing chamber therein, means for delivering liquid fuel to said mixing chamber, atomizing structure adjacent the point of delivery of said fuel, and means for continuously delivering into said mixing chamber tangentially thereof a stream of gas from said furnace.

5. The combination with a furnace, of a mixing chamber disposed therein, a system for circulating gases from said furnace to said chamber including rotary gas-moving mechanism for churning and thereby mixing the gases in the circulating system, an impact member disposed adjacent said chamber, and means external to said chamber and remote from said impact member discharging liquid fuel against said impact member.

6. The combination with a furnace, of a mixing chamber disposed therein, a circulating system for withdrawing gases from said furnace and delivering them tangentially into said chamber for inducing a whirl therein, an impact member, and means for directing a stream of liquid fuel against said member and into said chamber into the whirling gases therein, said chamber having a flame opening above the region of tangential delivery of gases, said circulating system drawing gases from said furnace at a region external to said chamber and adjacent said opening.

7. The combination with a furnace, of a mixing chamber disposed therein, a circulating system for withdrawing gases from said chamber and delivering them tangentially into said chamber for inducing a whirl therein, an impact member, means for directing a stream of liquid fuel against said impact member and into said chamber into the whirling gases therein, and means for delivering air into said furnace external to said chamber adjacent said chamber and in-

dependently of the intake of said circulating system.

8. The combination with a mixing chamber, of means for delivering hot gaseous products of combustion into said chamber tangentially for inducing a whirl therein, an impact member, and means delivering a jet of liquid fuel against said impact member, whereby said fuel is minutely subdivided and introduced into the whirling gas.

9. In the art of burning liquid fuel, the method which comprises atomizing the fuel, effecting contact of the atomized fuel with a whirling stream of hot gaseous products of combustion at a temperature sufficiently high to effect substantially complete vaporization of the fuel, and burning the vaporized fuel.

10. In the art of burning liquid fuel, the method which comprises effecting circulation of gaseous products of combustion, caus-

ing the circulating gaseous stream at a predetermined region in its circuit to partake of whirling movement, and effecting mixture and substantially complete vaporization 25 of the fuel in the still whirling gaseous stream.

11. The method of burning liquid fuel, which comprises introducing atomized fuel as such into a whirling stream of hot gaseous 30 products of combustion containing oxygen, and effecting substantially complete vaporization of the atomized fuel while in said whirling stream.

12. The method of burning liquid fuel, 35 which comprises introducing atomized fuel as such into a whirling stream of hot gaseous products of combustion containing oxygen, and effecting at least partial combustion of the fuel while in said whirling 40 stream.

JAMES B. SWORD.
